WALTHER KURZE, OF NIEDERLÖSSNITZ, NEAR DRESDEN, GERMANY, ASSIGNOR TO
THE FIRM OF H. P. KUEHNE, OF NIEDERLÖSSNITZ, NEAR DRESDEN, GERMANY.

ARMOR-PLATING FOR BATTLESHIPS.

1,179,113.

Specification of Letters Patent. Patented Apr. 11, 1916.

Application filed April 19, 1913. Serial No. 762,244.

To all whom it may concern:

Be it known that I, WALTHER KURZE, engineer, a subject of the King of Saxony, German Empire, and resident of Koenigstrasse 6, Niederlössnitz, near Dresden, Kingdom of Saxony, German Empire, have invented a new and useful Improvement in Armor-Plating for Battleships, of which the following is a specification.

10 This invention has reference to a new and improved system of armor plating for battleships or the like and has for its object to prevent as much as possible the penetration of heavy projectiles into the armor-plating
15 in general or for instance into the armor-plating of turrets, conning-bridges and the like in such a manner that the men, the apparatus or instruments for commanding, measuring and the like, the guns and steering
20 devices as well as the main armor-plating of the war-vessel itself are adequately protected against the destroying effect of the projectiles. It is of greatest importance to particularly prevent the penetration of
25 heavy projectiles into the central or middle part of armor-plated battle-ships, or into the commander's turret, from which not only the battle-ship itself but often also an entire squadron of war-vessels or even an entire
30 fleet is commanded as is well known.

According to the present invention the penetration of heavy projectiles into the armor-plating of battle-ships or war-vessels is obviated by entirely preventing the projectiles from coming into contact with the main armor-plating. For this purpose special protecting means for the said armor-plating are provided, said protecting means or devices being made to form protecting
35 armor-plates situated in front of the hopper or main armor-plating of the vessel and being arranged so as to travel or move laterally thus receiving a lateral displacement and at the same time yield in a rearward
40 direction in such a manner that on the impact of a projectile on the protecting armor-plate the latter will yield rearward and at the same time travel or move laterally into another position. In consequence of this
45 new position which the protecting plate will assume for a short time the projectile hitting the same will be caused to slide off said armor-plate without any considerable loss of

its kinetic energy. On the other hand, it will be necessary to maintain the kinetic 55 energy of the hitting projectiles for causing the recoil of the latter into the atmosphere, for preventing, during the sliding off movement of the projectiles, another or repeated contact with parts of the protecting-device 60 and, finally for obviating a continued loss of the kinetic energy of said projectiles which, in case of a repeated contact of the projectiles with the protecting device would be transformed into forces capable of destroying 65 the said armor-plating.

The main feature of the present invention therefore is the provision of means for so supporting protecting armor plates as to make the same capable of yielding rearwardly parallel to themselves as well as traveling or moving laterally, the yielding supports having a tendency of overcoming the inertia of a protecting armor plate even when a projectile strikes the same in its 75 middle or central part.

According to the present invention the protecting armor-plates are arranged in front of the armor-plating proper which in consequence of this double plating may be 80 made thinner and therefore will be of a less weight than heretofore. These protecting armor-plates are preferably of a curved shape and supported in such a manner that they will be capable of yielding rearward 85 and at the same time traveling or moving laterally. When a heavy projectile strikes against the same some of the kinetic energy of the projectile will be transferred to said plate and in consequence also to its movable 90 support, thus causing a lateral movement of the plate, inasmuch as the latter will travel or move laterally and thus change the point in which the projectile hits said plate, whereby the trajectory of flight of the projectile 95 is changed and a recoil of the latter back to the atmosphere is insured. By supporting the protecting armor-plate so as to be capable of traveling or moving laterally and at the same time of yielding rearward this 100 plate will have during its recoil sufficient time to receive and accumulate the energy transmitted to it and to transform said energy into the desired movement. The instability of the yielding support for the protecting armor-plate causes even in case a 105

projectile hits the plate centrally, the latter to vibrate whereby the yielding support will itself partake of this vibration sufficiently to remove the point, at which the projectile hit 5 the plate, from its central or middle part.

For the purpose of preventing superfluous continued lateral movement of the protecting armor-plate after the projectile has slid off and left the same, suitable stop-devices 10 and other devices, by which this plate will be returned to its position of rest, may be provided for.

The above mentioned arrangement for protecting the usual or main armor-plating 15 of war-vessels and the like may also be made use of for protecting particularly large vision-slots or sight-openings which, as is well known, were very often up to now only covered by very insufficient protecting devices. 20 If the protecting device forming the object of the present invention is used for these purposes, it must be so arranged or adjusted that only the small lateral vision-slots, sufficient to observe the enemy, will remain un- 25 covered, however of course in such a manner that they will not be exposed to the projectiles. It may in this case then be of preference to make use of a mirror-device.

The accompanying drawing shows one 30 constructional form of the subject matter of the invention as applied to conning-bridges that is for bulbed or circular armors.

Figure 1 represents a vertical transverse section. Figs. 2, 3 and 4 are horizontal 35 transverse sections respectively on lines $x-x$, $y-y$ and $z-z$ of Fig. 1 and Fig. 5 is a horizontal transverse section of an armor-turret provided with the protecting armor-plate constructed according to the 40 present invention.

a , Fig. 1, represents part of a stationary armor-plating covered by an armor-plate a^1 protecting the upper part of said armor-plating.

b is the yielding armor-plate capable of lateral movement and forming the object of the present invention. This armor-plate b is protected from above by the armor plated cover a^1 projecting for this purpose over the 50 upper edge of the yielding armor-plate b .

The armor-plate b is capable of a lateral movement or travel on ball-bearings c , d and roller-bearings e , f around the stationary armor-plating a . Flat springs g , h and 55 coiled springs i are provided between the back of the protecting armor-plate b and the stationary armor-plating a in such a manner that the protecting armor-plate b may yield toward the stationary plate a . During 60 this backward yielding movement of the protecting armor-plate b the springs fastened within said plate will touch the sector-shaped partitions or separating-plates k , l loosely inserted between the springs and 65 the stationary armor plating a in such a

manner that the partitions or separating plates will come into contact with the roller-bearings e , f respectively.

To insure a smooth as possible running of the ball-bearings the rollers e , f touch the armor-plating a and the movable protecting armor-plate only at the rings or bands m inserted into the periphery of the armor-plating a and into the inner faces of the separating plates k and l . The rollers are 70 movably inserted into the protecting armor-plate b by means of the coils i mentioned above and the roller-cages n as clearly seen from Figs. 1 and 2.

The movable protecting armor-plate b 75 rests against the ball-bearing c by means of the blocks o movably arranged within the said armor-plate b as shown by Figs. 1 and 4. Said blocks are provided with bolts p fastened to them and allowing a free or independent to and fro movement of the blocks within corresponding grooves o^1 provided in the protecting armor-plate b . The blocks are held by the covering rings q^1 , q^2 80 fastened in the inner face of the protecting armor-plate b so as to prevent a separation of the blocks from the protecting armor-plate. For supporting the blocks on or against the stationary armor-plating a , the bolts r are 85 inserted into and fastened to the blocks o and are provided on their upper tapered part or end with small rollers s rotating within the grooves t provided within the stationary armor-plating a and touching the 90 side walls of said grooves.

As represented in Fig. 3, the sector-shaped 95 partitions or separating-plates k are separated from the rollers again by the projections or flanges v , if the movable protecting armor-plate b returns to its original position, so that they will only serve substantially 100 for the transmission of the lateral impulse of force or impact. When the said partitions or plates are returned to their original position the protecting armor-plate b is again 105 free to move in any direction.

The ball-bearing d is provided in the upper part of the protecting armor-plate for additionally supporting this plate 110 against falling out laterally and, by its coil u for receiving the recoil of the armor-plate b produced by the springs resting against 115 said plate.

Fig. 5 shows diagrammatically the use of the object of the present invention with a 120 gun protected by armor plate. The gun or ordnance itself being guided within small or narrow embrasures, a device must be provided for preventing a contact between the gun and the movable protecting armor-plate b . Said device may be formed by a limiting block w inserted into the stationary armor-plating in a resilient manner by coiled springs z so that it may yield in all 125 directions. This block w engages a groove 130

or grooves provided in the movable protecting armor-plate and is loosely connected by a pin *x* with the stationary armor-plating *a*.

- 5 The means described for protecting a gun arranged within an armor-plated turret will act in such a manner that on a projectile hitting the outer protecting armor-plate the latter will be capable of traveling peripherically to the inner stationary armor-plating and moving around a point coinciding with the center of the latter. The recoil of the protecting armor-plate may also be produced by a motive fluid under 10 pressure instead of coiled springs.

I claim as my invention:

1. In an armor-plating for battle-ships or the like, the combination with stationary armor-plates to be protected, of protecting 20 armor-plates, yielding supports for simultaneously allowing the protecting armor plates to travel laterally and yield rearwardly, and means for fastening said supports of the protecting armor-plates to the 25 interior faces of the latter and to the outer surfaces of the stationary armor-plates to be protected.

2. In an armor-plating for battle-ships and the like, the combination with stationary 30 armor-plates to be protected, of protecting armor-plates, yielding supports for simultaneously allowing the protecting armor-plates to travel laterally and yield rearwardly, means for fastening said supports of the protecting armor-plates to the 35 interior faces of the latter and to the outer surfaces of the stationary armor-plates, elastic means for reducing the friction caused between the moving parts of the 40 movable protecting armor-plates and the stationary armor-plates, and rolling supports for uniformly distributing the weight of support of the moving parts mentioned.

3. In an armor-plating for battle-ships and the like, the combination with stationary armor-plates to be protected, of protecting 45 armor-plates, supports for simultaneously allowing the protecting armor-plates to travel laterally and yield rearwardly, means for fastening said supports of the protecting armor-plates to the 50 interior faces of the latter and to the outer surfaces of the stationary armor-plates, rolling supports for reducing the friction 55 caused between the moving parts of the movable protecting armor-plates and the stationary armor-plates and for uniformly distributing the weight or support of the moving parts mentioned, and elastic means 60 for allowing the temporary contact of the protecting movable armor-plates with the stationary armor-plates only during the moment of impact caused by the striking projectile.

4. In an armor-plating for battle-ships or

the like, the combination with stationary armor-plates, blocks for freely connecting the stationary armor-plates with the movable protecting armor-plates, ball-bearings for supporting said blocks, yieldingly arranged 70 roller-bearings, flat-recoil springs, separating plates loosely arranged between said 75 springs and roller bearings, ring shaped bands provided within the outer surface of the stationary armor-plates to be protected, 75 and flange-shaped projections inserted into the inner surface of the protecting armor-plates and separating the groups of rollers belonging to one protecting armor-plate from the groups of rollers belonging to the 80 adjacent protecting armor-plates.

5. In armor-plating for battle-ships and the like, and in combination, a stationary armor-plate to be protected, a protecting 85 armor-plate, block members for connecting the said stationary armor-plate and protecting armor-plate so that the latter may move toward and away from the former, ball bearings in which the same are mounted, and roller-bearings permitting the said protecting armor-plate, when struck, to also move laterally and in front of the said 90 stationary armor-plate.

6. In armor-plating for battle-ships and the like, and in combination, a stationary 95 armor-plate to be protected, a protecting armor-plate, block members for connecting the said stationary armor-plate and protecting armor-plate so that the latter may move toward and away from the former, ball 100 bearings in which the same are mounted, roller bearings, frames in which the said roller bearings are journaled, the said frames being mounted in the said protecting armor-plate and the roller bearings adapted 105 to contact with the outer surface of the said stationary armor-plate, and resilient means for normally maintaining the said roller bearings, frames, and consequently the said protecting armor-plate, in position. 110

7. In armor-plating for battle-ships and the like, and in combination, a stationary armor-plate to be protected, a protecting 115 armor-plate, block members for connecting the said stationary armor-plate and protecting armor-plate so that the latter may move toward and away from the former, ball bearings in which the same are mounted, roller bearings, frames in which the said roller bearings are journaled, the said frames being mounted in the said protecting armor-plate, and the roller bearings adapted to contact with the outer surface of the said stationary armor-plate, springs extending between the said frames in which the roller 120 bearings are mounted and adjacent portions of the said protecting armor-plate, separating plates extending between the said frames and lying adjacent the said roller bearings, and additional springs between 125 130

the said separating plates and inner surfaces of the said protecting armor-plate.

8. In armor-plating for battle-ships and the like, and in combination, a stationary armor-plate to be protected, a protecting armor-plate, block members for connecting the said stationary armor-plate and protecting armor-plate so that the latter may move toward and away from the former, ball 10 bearings in which the same are mounted, roller bearings, frames in which the said roller bearings are journaled, the said frames being mounted in the said protecting armor-plate, springs extending between the 15 said frames in which the roller bearings are mounted and adjacent portions of the said protecting armor-plate, separating plates

extending between the said frames and lying adjacent the said roller bearings, additional springs between the said separating plates and inner surfaces of the said protecting armor-plate, rings set in the faces of the said separating plates and rings set in the outer face of the said stationary armor-plate, against which said rings the said 20 25 roller bearings are adapted to contact.

In testimony, that I claim the foregoing as my invention, I have signed my name in presence of two witnesses, this 31st day of March, 1913.

WALTHER KURZE.
